SHIRT

Max Shapiro, Brighton, Mass.

Application June 30, 1948, Serial No. 147,309

Term of patent 3½ years

(Cl. D3—25)

To all whom it may concern:

Be it known that I, Max Shapiro, a citizen of the United States, residing in Brighton, county of Suffolk, and State of Massachusetts, have invented a new, original, and ornamental Design for a Shirt, of which the following is a specification, reference being had to the accompanying drawing, forming a part thereof, in which: Figure 1 shows a front view of the shirt showing my new design and Figure 2 shows a rear view of the shirt.

I claim:

The ornamental design for a shirt as shown.

MAX SHAPIRO.
